DATA TELECOMMUNICATION SUBSET

James N. Burlin, New York, N.Y., Henry Dreyfuss, South Pasadena, Calif., Stanley E. Serefny, Indianapolis, Ind., and Edward M. Smith, Montclair, N.J., assignors to Bell Telephone Laboratories Incorporated, New York, N.Y., a corporation of New York

Filed Aug. 1, 1961, Ser. No. 66,160

Term of patent 14 years

(Cl. D26—14)

FIG. 1

FIG. 2

FIG. 3

FIG. 1 is a perspective view of a data telecommunication subset showing our new design;

FIG. 2 is a front view of the data telecommunication subset; and

FIG. 3 is a side view of the data telecommunication subset.

The essential features of the new design reside in the portions shown in full lines.

We claim:

The ornamental design for a data telecommunication subset, substantially as shown and described.
